UNITED STATES PATENT OFFICE.

CYRUS W. BALDWIN, OF YONKERS, NEW YORK, ASSIGNOR TO WILLIAM E. HALE, OF CHICAGO, ILLINOIS.

ELECTRIC IGNITER FOR GAS-ENGINES.

SPECIFICATION forming part of Letters Patent No. 352,796, dated November 16, 1886.

Application filed July 11, 1884. Serial No. 137,436. (No model.)

To all whom it may concern:

Be it known that I, CYRUS W. BALDWIN, of Yonkers, county of Westchester, State of New York, have invented certain Improvements in Electric Igniters, of which the following is the specification.

My invention relates to that class of exploders for gas-engines in which an electric spark is made the means of igniting the explosive charges; and my invention consists in means, fully described hereinafter, for maintaining the exploder in constant effective condition.

In the drawings, Figure 1 is a longitudinal section of the head of the cylinder of a gas-engine illustrating my improvement. Fig. 2 is an end view of Fig. 1.

A represents the cylinder-head of a gas-engine, which is connected by the bolts *a* to a cylinder of any suitable construction, and which, as it forms no part of the present invention, is not illustrated. The head, instead of being solid, as usual, is hollow, containing a water-chamber, *x*, through which water flows either from pipes connected to the head or through suitable connections or channels with the water-space of the cylinder.

In the center of the head *A* is an opening or perforation adapted for the reception of a threaded tube, *c*, constituting the outer shell of the igniter-plug *D*, provided with a detachable cap, *d*, at the inner end, and with a detachable block, *f*, at the outer end, through which block extend two conducting-wires, *e e*, terminating in platina electrodes *i i*, which are set at a slight distance apart, as shown. The space within the shell of the plug and around the wires *e e* is filled with a suitable artificial cement or stone— as, for instance, a composition of pumice-stone and water cement, or other suitable non-conducting material—which can be inserted in a plastic state, and which will harden, so as to form a solid body around the wires.

The wires *e e* are put in communication with the wires of an electric circuit which is made and broken in any suitable manner, so as to throw a series of sparks intermittently between the electrodes at proper intervals to explode the charges within the cylinder.

Heretofore efforts have been made to explode

the charges in gas-engines by means of electric sparks, but, so far as I am aware, without practical success, the ill results being attributed in most instances to defects in the electrical appliances and the variations in the current.

I have discovered that the difficulty in securing uniformly good results has been caused by the heating of the electrodes and their supports, resulting, among other things, in the partial destruction of such supports and the escape of the compressed gases. I have also discovered that by surrounding the supports for the electrodes with a chamber through which water is caused constantly to flow the parts may be maintained at such a temperature as to preserve them at all times and under all circumstances in an effective working condition.

In the construction shown in the drawings, and above described, the water in the chamber *x* surrounding the plug serves to maintain the latter and its adjuncts at the required low temperature.

I do not limit myself to the construction of plug and mode of setting the electrodes shown, and above described, inasmuch as these may be varied without departing from the main features of my invention; nor do I limit myself to the use of a screw-plug, nor to one inserted in the head of the cylinder, as different means of holding the plug in place may be employed, and it may be set in any desired position in respect to the cylinder or head.

The cap *d* serves to secure the filling tightly in place and keep it from working loose, which is important, as any play of the filling soon renders the device inoperative.

I am aware that gas-engines have been heretofore provided with electrical igniters wherein a plug containing conducting-wires, one of which is insulated by porcelain from the plug, is surrounded by water, and I therefore do not broadly claim such construction.

Without limiting myself to the precise construction and arrangement of parts shown, I claim—

1. In an exploder for gas-engines, the combination, with the engine-cylinder, of a hollow shell extending through the cylinder, wires passing through said shell, insulated therefrom and provided with electrodes, and a surround-

ing body of artificial stone or cement, substantially as described.

2. The combination, in a gas-engine, of a cylinder having a perforation and a surrounding water-space, an electric exploder consisting of a shell fitting said perforation, and wires passing through said shell, insulated therefrom and provided with electrodes, substantially as described.

3. The combination of the hollow shell, its filling, conductors, electrodes, and cap, with a gas-engine, substantially as described, for the purpose set forth.

4. An exploder comprising a hollow shell, a plug fitted to one end thereof, and conductors passing through and insulated from said shell, in combination with the cylinder or head of a gas-engine, and with a water-chamber which surrounds said exploder, substantially as described.

5. A hollow shell having its exterior and interior provided, respectively, with male and female screw-threads, a screw-threaded plug engaging said female screw-threads to close

one end of said shell, conductors passing through said plug and shell to support electrodes, and non-conducting material surrounding said conductors within said shell, substantially as described.

6. A hollow shell having its exterior and interior surfaces, respectively, provided with male and female screw-threads, a screw-threaded plug to engage said female screw-threads, and conductors provided with electrodes passing through said plug and shell and insulated therefrom, in combination with a cylinder or cylinder-head, and with water-receiving chambers within said cylinder or cylinder-head and surrounding said hollow shell, substantially as described.

In testimony whereof I have signed my name to this specification in the presence of two subscribing witnesses.

CYRUS W. BALDWIN.
